DRYING APPARATUS

William Strobridge, Syracuse, N. Y., assignor to
 United States Hoffman Machinery Corporation,
 New York, N. Y., a corporation of Delaware

Application January 4, 1937, Serial No. 119,029

9 Claims. (Cl. 34—5)

This invention pertains to an improved drying apparatus which may be employed for removing moisture from garments and the like. The apparatus also lends itself equally to the removal of 5 cleaning fluid and its odor from garments or the like which have been treated with such fluids.

The structure is disclosed in the annexed drawings, wherein:—

Figure 1 is a front elevation of the machine with 10 the door leading to the drum shown in its closed position;

Fig. 2, a fragmentary horizontal sectional view 15 of the door and door frame, the line of section being substantially indicated at II—II on Fig. 1; Fig. 3, a rear elevation of the machine, partly broken away, and with certain portions in section;

Fig. 4, a vertical axial section of the machine; and

Fig. 5, a diagrammatic view illustrative of the 20 of the flow of the heated air through the apparatus.

The machine of the present invention is of that type wherein a rotary perforate drum is mounted 25 upon a horizontal axis within a casing, and the clothes which are introduced into the drum and cascaded therein as the drum is rotated about its axis, are subjected to the drying action of heated air.

The main object of the present invention is to 30 so construct the apparatus that the heated air is introduced directly into the drum where it first contacts the goods to be treated, and then passes outwardly through the perforate wall of the drum 35 to an exhaust passage or offtake. By such an arrangement, the air at its highest temperature initially expends its energy or gives up its heat 40 to the treatment of the articles being cascaded within the drum, before contacting the perforate wall of the drum. In other words, the arrangement is such that the heated air which is introduced into the central portion of the drum or about and around the axis thereof, first contacts 45 the goods in the drum and is then drawn outwardly through the perforate drum wall to an exhaust fan through which the vapor-laden air is discharged.

A further object of the invention is to provide 50 a structure wherein means is present to cause the air to follow the path above outlined, without undue impedance. The parts are, however, so proportioned and arranged as to evenly distribute the flow of air outwardly of the apparatus.

With these and other objects in view, reference 55 will be had to the accompanying drawings, where-

in 10 designates the base of the machine which is supported upon feet 11. An upstanding jacket or housing 12 is secured to the base 10 and extends upwardly from three sides thereof, the fourth or rear open side being partly closed by a plate 13 secured to the side elements 14 and 15 of the housing 12.

The housing 12 supports an annular shell 16 having its two ends closed by plates 17 and 18, respectively. The front plate 17 is formed with an offset flange or rim 19 which is secured to a flange 21 of shell 16 by means of a clamping ring 22. The ring 22 is U-shaped in cross-section to receive and embrace the flanges 19 and 21, and its two ends are drawn toward each other by 15 means of a bolt 23 and nut 24, and in this way securely bind the parts together.

A circular opening formed centrally of the 20 plate 17 receives a door and door frame assembly, through which loading and unloading of the machine may be effected. The door frame, which is best shown in Fig. 2, may be said to comprise an annular flange 25, having formed as an integral part thereof an inwardly extending cylindrical member or portion 26.

The flange 25 lies against the outer face of the 25 front plate or element 17 and is secured thereto by suitable bolts or the like designated by 27, as best shown in Fig. 4. The cylindrical member 26 may be apertured, or in other words, may be 30 be provided with a series of elongated openings 28 in the upper portion thereof, and the shell 16 is likewise provided with a series of openings 29 in that portion or end which overlies the annular member or element 26. The purpose and function 35 of the openings 28 will hereinafter appear.

To close the outer end of the member 26, into 40 and through which the articles to be dried are introduced and withdrawn, there is provided a door 31 which is of such dimensions as to overlie the flange 25 to make close contact therewith when the door is fully closed and secured in position.

The door is a hinged one, and in the form illustrated, the supporting element may be said to 45 comprise a Y-shaped casting 32, the outer ends of which cooperate with a pintle or pin 33, which, in turn, is supported by gudgeons or lugs 34 extending outwardly from the flange 25.

The casting or hinge element 32 is provided 50 with a hollow element or member 35 (Fig. 2), which stands in line with the center of the door and a bolt 36 extends through the door and through the outer wall of the member 35. A compression spring 37 encircles the bolt 36 and a lug 38 extending inwardly from the outer wall of 55

the member 35, so as to always exert sufficient pressure upon the door to force it tightly toward its seat. This ensures tight closure of the structure except for the intake of air hereinafter referred to and the passage leading to the exhaust fan.

When the door is closed and with the parts as shown in full lines reference being had more particularly to Figures 1 and 2 a latch 39 pivoted to the free end of the casting 32 is designed to be thrown downwardly into contact with a fixed keeper 41 carried by the door frame. By swinging the latch 39 upwardly the door may be readily unlocked and swung clear of the opening formed by the cylindrical member 26 and thus afford full access to a drum mounted within the casing for rotation therein.

Said drum is cylindrical in contour and its outer wall, designated by 42, is perforate throughout 20 and has secured at opposite ends, heads 43 and 44, respectively. Head 43 is imperforate and the same is true of the head 44 except for a large central opening formed therein defined by an inwardly extending flange 45 which surrounds the 25 inner portion or end of the member 26 in spaced relation thereto.

As will be best seen upon reference to Fig. 2, the inwardly extending flange 45 is curved, and together with the adjacent portion of the member 26, forms an annular orifice denoted by 45a. This annular space is, in effect, a nozzle through which the indrawn air is normally caused to pass, and by reason of the curvature of the member 45, friction or resistance is at the minimum.

To render the drum structure stable and likewise to produce a cascading effect of the goods within the drum when the same is rotated, there is preferably provided a series of lifter elements which may be formed in various ways. In the instant case, they are produced from sheet metal bent to form, the sheets being folded upon themselves into a general V-shape in cross-section, so as to produce the lifter which is designated generally by 46. The inner edges of these plates 45 may be welded to the perforate wall of the drum or otherwise secured thereto, and through bolts 47 extend from head to head of the drum and are housed within the fold of the V.

Thus, rigidity is imparted to the drum, and this is a matter of moment, inasmuch as it is supported from one end only.

In order to support the drum, there is secured to the outermost face of the head 43, a plate-like casting or element 48 having strengthening ribs 55 49 radiating from a centrally disposed hub-like element 51, the outer end of which is reduced, forming a stub shaft 52. Said stub shaft extends into a housing or casting 53 in which it finds its support, suitable roller bearings or the like (not shown) being provided at the outer end of the shaft and at the inner portion thereof adjacent the hub. Stub shaft 52 has secured to it (see more particularly Fig. 3), a sprocket 54 about which passes a sprocket chain 55, which 65 chain also passes about a second sprocket 56 mounted upon a counter-shaft 57 driven by an electric motor 58, or other suitable source of power.

The drum adjacent what may be termed the 70 intake or forward end thereof, has secured to its outer face adjacent the forward head or wall 44, a suitable packing 50 which extends entirely around the same and contacts the inner face of the annular shell or casing 16. As shown, this 75 packing is U-shaped in form and when produced

from heavy felt or the like will, by reason of its U-shape, spring outwardly and closely contact the adjacent wall of the casing, forming a continuous seal between the rotatable drum and the casing. Thus, passage of air around the end of the drum at this point is precluded. Any form of seal and the securement thereof at this point to effect a seal between the drum and the casing can, of course, be used, but that shown and just alluded to is found effective in operation and 10 possesses a long life.

As above indicated, heated air is designed to be drawn into the rotating drum and directly into contact with the goods which are being cascaded therein, prior to its outward passage through the 15 perforate wall of the cylinder. Preferably, a chamber as 59 will be formed or mounted upon the upper end of the cylindrical shell or casing 16, and a suitable heating element is mounted in the intake end of said casing, which end is open 20 to the atmosphere. Said heating element may be of the form illustrated, to wit, a fin heater designated generally by 61, having a supply pipe 62 for steam of the desired temperature and an offtake pipe 63, to ensure proper circulation 25 through the coils. To provide for the tempering of the air in case it becomes too hot, a slide or other suitable valve 64 is provided to control openings, as 65 and 66, formed in the wall of the element 59.

The motor 58 in addition to imparting rotary motion to the drying drum, likewise, in the instant case, is employed to actuate an exhaust fan denoted generally by 67. The eye of the fan, as will be best seen upon reference to Figs. 3 and 4, 35 is connected to a relatively large conduit 68, the upper end of which terminates in an opening formed in the rear wall 18 of the casing, said opening being preferably located at the lower portion of the casing, or at a point considerably 40 below the axis of the drum.

In Fig. 5, the apparatus is shown in the dia- 45 grammatic or outline form, this with a view of clearly indicating the passage of the air through the apparatus. Upon looking at this figure, it will be seen that the incoming air passes into the upper portion of the structure where it is heated, thence is drawn downwardly through the openings 29 and through the nozzle or space 45a, and is thus projected centrally into the drum. 50

Under certain conditions, the air may pass through the openings or apertures 28 in the sleeve-like member 26 and into the drum in the event that the cascading articles being treated in the drum should tend to close off portions of 55 the main air inlet, to wit, the nozzle 45a.

The air is precluded from passing around the end of the drum or cylinder and exteriorly of the same by the packing 50, which seals off the space between the outer wall of the drum and 60 the casing; thus, short-circuiting of the air is precluded and it must all pass axially and inwardly into the drum.

The air is thus brought into direct contact with the goods which are being cascaded within the 65 drum, contacting the same prior to any contact with the perforate wall of the drum, and the heat units are given up first to the goods and not primarily to the drum.

After absorbing or taking up moisture from 70 the articles or goods, the air is drawn outwardly through the perforate drum wall 42 into the casing and to the offtake opening with which the pipe 63 is connected. Some air as it is first introduced into the rotary drum will, of course, 75

pass directly to the perforate wall of the drum, but in the main the greater volume directly contacts the goods being cascaded.

Reference is again made to Figures 4 and 5, wherein the path of flow of the air may be readily followed, and wherein it will be seen that the cylindrical shell or wall 42 of the drum extends past the head 43 toward the rear wall 18 to a considerable extent. Such portion is imperforate and an annulus 60 is thus produced through which the outgoing air must be drawn. The width of this annulus is such as to cause an even distribution of the flow of air outwardly from the drum.

In use the drum is, of course, rotated while the air is being drawn into and through the apparatus. The goods with contained water or cleaning fluid may be introduced through the member 26 when the door 31 is opened, and this while the drum is stationary or rotating. As will be appreciated by those skilled in the art, the articles are primarily extracted before introduction into the present apparatus, so that there is no necessity for any free water or cleaning fluid offtake, the residual moisture being evaporated by and carried off with the heated air through the exhaust fan.

What is claimed is:

1. A drying apparatus, comprising a casing; a hollow drying cylinder rotatably mounted within said casing, said cylinder comprising a perforate peripheral wall and two end walls, one of said walls being imperforate and the other of said end walls having a circular opening formed centrally therein, the adjacent wall of the casing likewise having a circular opening therein in axial alignment with the circular opening formed in the end wall aforesaid; a closure for the opening in the casing; means for sealing the cylinder adjacent the last named end wall with reference to the casing to prevent the passage of air between said parts at this point; an annular flange carried by the casing and extending inwardly into the central opening in the adjacent end wall of the cylinder, the outer peripheral face of said flange standing in spaced relation to the edge of the opening in the cylinder wall, forming therewith an orifice through which air may be drawn in an axial direction into the cylinder; and means for drawing air through said orifice into the central portion of the cylinder and outwardly through the perforate peripheral wall thereof.

2. An apparatus as set forth in claim 1, wherein the circular opening formed in the wall of the cylinder is defined by a flange which is curved inwardly toward the axis of the drum, thereby forming in effect with the annular flange carried by the casing, an annular nozzle.

3. An apparatus as set forth in claim 1, wherein the annular flange carried by the casing is provided with apertures in that portion thereof which lies between the adjacent head of the cylinder and the adjacent wall of the casing.

4. An apparatus as set forth in claim 1, wherein the annular flange carried by the casing is provided with a series of apertures in the upper portion thereof through which the air may be drawn to pass inwardly into the drying cylinder.

5. A drying apparatus, comprising a casing embodying a front and a rear wall, the front wall being provided with an opening for the introduction and removal of goods to be treated; a door for closing said opening; a hollow drying cylinder rotatably mounted within said casing, said cylinder comprising a perforate peripheral

wall and two end walls, the rear wall being imperforate and the other of said walls having a circular opening formed centrally therein in line with the opening formed in the front wall of the casing; means for sealing the periphery of said cylinder with reference to the shell at the intake end of the cylinder against the passage of air longitudinally of the cylinder; an annular collar secured to the inner face of the front wall of the casing and projecting into the opening in the front wall of the cylinder, said collar being provided with apertures; and means for drawing air into the cylinder from said apertured collar and discharging it outwardly of the casing.

6. A drying apparatus, comprising a casing having a door opening therein; a closure for said opening; a drum rotatably mounted in said casing, said drum having a perforated peripheral wall, a closed end wall, and an end wall having a circular central opening therein; an annular flange around said door opening and extending inwardly into said central opening and forming an annular orifice between the flange and the edge of the wall which defines said central opening; means for sealing the drum with reference to the adjacent wall of the casing at that end wall of the drum in which the opening is provided for the introduction of the material to be dried and the subsequent withdrawal therefrom to prevent entrance of air longitudinally between said parts at this point; and means for drawing air through said annular orifice and axially into said drum, the air passing through the periphery of said drum and out of said casing at that end remote from said door opening.

7. A drying apparatus comprising a casing having an inlet opening in one end wall and an exhaust opening in the other end wall; a hollow drying cylinder rotatably mounted in said casing, said cylinder having a perforate periphery, an imperforate end, and an end spaced from the casing inlet, said end having a circular centrally disposed opening therein; an annular apertured flange secured to said casing around the inlet opening and extending inwardly into the perforate end of said cylinder; means for directing air into said casing through the apertures in said flange and axially into said cylinder; and means connected to the exhaust opening in said casing for withdrawing air radially from said cylinder.

8. A drying apparatus, comprising a casing having a front wall with an opening therein for the introduction of material to be treated, and an oppositely disposed wall having an exhaust opening therein; a hollow drying cylinder rotatably mounted in said casing, said cylinder having a perforate periphery, an imperforate inner end, and an end spaced from the front wall of the casing, which end is formed with an opening aligning with the opening in said front wall; an annular perforated flange on said casing encircling the opening in the front wall of the casing, said flange extending inwardly into the opening in the adjacent cylinder end; a heater shell mounted on said casing; a heater in said shell in direct communication with the atmosphere and with an inlet opening in said casing adjacent the upper portion thereof; means located between said heater and said inlet for admitting fresh air to said inlet; and means connected to the exhaust opening in the casing for withdrawing vapor-laden air from said cylinder.

9. A drying apparatus, comprising a rotatable cylinder having openings in its periphery, one

end closed and the other with an opening therein; a casing enclosing said cylinder, said casing having an inlet at one end in registry with the opening in the cylinder and an exhaust opening adjacent the closed end of the cylinder; a closure for the casing inlet; a flange between the casing inlet and the opening in said cylinder, said flange having at least one aperture therein; means for directing heated air through the aperture and

axially into said cylinder; means for exhausting air radially from said cylinder; and an annular packing between the periphery of the drum adjacent that end having the opening therein and the peripheral wall of the casing for isolating the cylinder inlet from the annular space between the periphery of the cylinder and the casing. 5

WILLIAM STROBRIDGE.
